FOLDING BED

Arthur G. Gilson, Fort Smith, Ark., assignor to
 Mitchell Manufacturing Company, Fort Smith,
 Ark., a corporation of Arkansas

Application September 28, 1936, Serial No. 102,840

3 Claims. (Cl. 5—168)

My invention relates to a folding bed and more particularly to that form of bed which may be readily moved when in its folded or vertical position so that it may be conveniently stored 5 in a closet or similar receptacle when not in use. My invention consists in improvements in the details of construction of such a bed and especially to the stabilizing means for supporting the bed frame and foot board when these parts are 10 moved from vertical to horizontal position or vice versa.

In the accompanying drawings which illustrate one form of bed made in accordance with my invention Figure 1 is a side view showing the bed 15 in horizontal position; Figure 2 is a side view showing the bed in vertical position; Figure 3 is a longitudinal section through the head part of the bed showing the parts in an intermediate position; Figure 4 is a section taken on the line 20 4—4 of Figure 3; Figure 5 is a side view showing the parts in an intermediate position; Figure 6 is a section taken on the line 6—6 of Figure 5; and Figure 7 is a section taken on the line 7—7 of Figure 6.

25 The numeral 10 designates the head board of the bed to which are secured the side frames 11 supported on the usual casters 12. Carried by each of the frames 11 is an upper supporting bar 13 and a lower supporting bar 14. Pivoted in bars 13 by means of trunnion 15 is the main or 30 mattress frame 16 which is thus adapted to be swung from the horizontal position shown in Figure 1 to the vertical position shown in Figure 2. The foot board 17 is pivoted to the main frame 35 16 by means of two links 18 and 19, respectively, to permit the foot board to be swung into parallel relation to frame 16 when the latter is moved into vertical position.

The stabilizer comprises a pair of levers 20 and 40 21 arranged at each side of the main frame and having their upper ends pivoted at points 22 and 23, respectively, to a bracket 24. The lower ends of levers 20 and 21 are pivoted at points 25 and 26, respectively, to a stabilizer caster 27. 45 It is to be noted that pivot points 22, 23, 25 and 26 are so related that levers 20 and 21 are maintained in approximately parallel relation during the movement of the main frame from vertical to horizontal position and that caster 27 is held 50 in vertical position during such movement so as to make proper contact with the floor. One of the levers 20 or 21, preferably the latter, is connected by a cross bar 28 (Figures 5 and 6) with the corresponding lever at the opposite side of

the bed to insure the simultaneous movement of the two pairs of levers.

Pivoted to lever 21 at a point adjacent pivot 23 is a link 29 having at its inner end a short slot 30. This slot engages with a pin 31 in a strut 32 pivoted at 33 to bar 13 and having an adjustable connection with bar 14. This connection may be provided by means of a bolt 34 passing through an arcuate slot 35 (Figure 3) in the strut and provided with locking nuts 36. 10

If the bed is placed on an uneven floor it may happen that not all the supports make contact therewith. In such case the nut 36 at one or both sides of the bed, as may be required, but usually only at one side, is loosened to permit 15 the strut 32 to be moved until an adjustment is obtained to secure proper contact, after which the nut or nuts is again tightened. In order that this adjustment may be made without disturbing the proper parallel position of parts 10, 16, and 20 17 when the bed is in raised position, lost motion must be introduced into the connection. Such lost motion is provided by the pin and slot connection 30, 31. Secured to link 29 is a bracket 25 37 (Figure 6) through which passes a threaded rod 38 attached to one end of a spring 39, the other end of which is attached to some part of the head structure, preferably to bolt 34. This spring functions to take up the lost motion and hold the caster 27 firmly against the floor and 30 its tension may be adjusted by means of a nut 40 on the threaded rod 38.

In this type of bed some type of counterbalance is necessary for the main frame. In Figure 3 I have shown one form of such counterbalance 35 consisting of springs 41 connected to a plate 42 extending between the side frames 11 and to a plate 43 carried by the main frame. While the foot board may be moved relative to the main frame manually, I prefer to secure automatic movement of this part by means of a connecting rod 44 pivoted to link 19 and some part of the head structure such as bar 14. 40

The operation of my bed is briefly as follows: 45 When the bed is in horizontal position, as shown in Figure 1, it is supported at the head by contact of the casters 12 with the floor and at the foot by contact of the legs of the foot board 17 therewith. The frame 16 is stopped in horizontal position by engagement of the foot rail of 50 the frame with the upper edges of links 18 which are positioned on the inner sides of the frame side rails for this purpose. To place the bed in folded or movable condition, frame 16 is grasped and 55 swung into vertical position on its trunnions 15, 55

as shown in Figure 2. The rod 44 operates to automatically fold the foot board so that both hands may be employed to raise the frame. During the raising operation the casters 27 are maintained in contact with the floor and provide an auxiliary support to prevent tipping of the bed which would be liable to occur if the limited base provided by casters 12 were depended upon alone. In case the floor is uneven, it may be found that the casters 27 do not properly contact the floor when the bed is in open position and pins 31 engage the inner ends of slots 30, as shown in Figure 5. In this case nuts 36 are loosened and struts 32 adjusted to secure the desired condition. Due to unevenness of the floor, it may occur during the raising or lowering of frame 16 that one of the casters 27 must rise above or fall below the level of the other. This is permitted by the movement of one or the other of the pins 31 in its cooperating slot 30. It will be understood that while the two pairs of levers 20-21 are compelled to substantially simultaneous movement by the cross bar 28, this bar is capable of sufficient flexure to permit the necessary relative movement to compensate for unevenness of the floor. Springs 39 compensate for the lost motion of the pin and slot connections and prevent rattling therein.

Having fully described my invention, what I claim as new and desire to secure by Letters Patent of the United States is:

1. In a device of the class described the combination with a head structure, of a mattress frame pivoted to said head structure to swing from vertical to horizontal position, a pair of levers pivoted to the mattress frame at one end, said levers being pivoted to a caster at the other end, a link pivoted to one of said levers and

provided with a slot, a strut pivoted to the head structure and carrying a pin engaging with the slot, and means for adjusting the strut on its pivot.

2. In a device of the class described the combination with a head structure, of a mattress frame pivoted to said head structure to swing from vertical to horizontal position, a pair of levers pivoted to the mattress frame at one end, said levers being pivoted to a caster at the other end, the pivot points of said levers to the frame and caster having such relation that the levers are maintained in approximately parallel relation and the caster in approximately vertical position during the movement of the parts, a link pivoted to one of said levers and provided with a slot, a strut pivoted to the head structure and carrying a pin engaging with the slot, means for adjusting the strut on its pivot, and a spring interposed between the link and the head structure for biasing the caster toward the floor.

3. In a device of the class described, the combination with a head structure, of a mattress frame pivoted to said head structure to swing from vertical to horizontal position, a pair of levers pivoted at one end to each side of the mattress frame, each pair of said levers being pivoted at the other end to a caster, a bar forming a rigid connection between one lever of each pair and the head structure, each of said bars including a loose connection between the bar and head structure forming a lost motion device to accommodate unevenness of a floor without adjustment of the connections, and a spring attached at one end to one of the connections and at the other to the head structure for taking up the lost motion in said loose connections.

A. G. GILSON.
